DESIGN FOR A SOFT HAT

Julius N. Wolf, Philadelphia, Pa.

Application September 4, 1935; Serial No. 58,426

Term of patent 7 years

To all whom it may concern:

Be it known that I, Julius N. Wolf, a citizen of the United States, residing in Philadelphia, Pennsylvania, have invented a new, original, and ornamental Design for a Soft Hat, of which the following is a specification, reference being had to the accompanying drawing, forming part thereof, in which—

Fig. 1 is a front top perspective view of a soft hat embodying the design; and

Fig. 2 is a plan view thereof.

The characteristic feature resides in the de-

sign of the brim, the two front opposite corners or temple portions being wider than the sides of the brim and also wider than the front or forehead portion of said brim so that said brim will produce when "snapped" a square effect when viewed from in front.

I claim:

The ornamental design for a soft hat, substantially as shown and described.

JULIUS N. WOLF.
